United States Patent Office

Des. 182,736
Patented May 6, 1958

182,736

HANDBAG OR SIMILAR ARTICLE

Gladys Murray, New York, N. Y., assignor to Bernard Cahn Co., Inc., New York, N. Y.

Application December 12, 1957, Serial No. 48,882

Term of patent 7 years

(Cl. D87—3)

I claim:

The ornamental design for a handbag or similar article, substantially as shown.
